UNITED STATES PATENT OFFICE.

WARREN R. WALKER, OF BLOOMFIELD, NEW JERSEY, ASSIGNOR TO COOPER HEWITT ELECTRIC COMPANY, OF HOBOKEN, NEW JERSEY, A CORPORATION OF NEW JERSEY.

ROTATING CYLINDRICAL GLASS MERCURY SWITCH.

Application filed January 20, 1927. Serial No. 162,267.

The present invention relates to electric switches of the liquid flow type and to mountings for holding them in suitable positions for moving them to break and make circuit therethrough.

Various objects and advantages of the invention will be obvious from the following particular description of one form of apparatus embodying the invention or from an inspection of the accompanying drawing; and the invention also consists in certain new and useful features of construction and combinations of parts hereinafter set forth and claimed.

15 In the accompanying drawings there is shown for purposes of illustration one form of apparatus embodying the invention, in which

20 Fig. 1 is a front elevation view of a switch unit involving the invention for mounting to a wall, a flush plate being part of the unit,

25 Fig. 2 is a vertical mid section of a unit mounted in a wall,

30 Fig. 3 is an end elevation view of the unit taken along the lines 3—3 of Fig. 2 and looking in the direction of the arrows,

35 Fig. 4 is a face view of the flush plate used in the illustration and

40 Fig. 5 is a back view of a handle member of the switch.

In the drawings the flush plate 1 set over the recess 2 in the wall 4 carries the inwardly extending bracket 6 which carries the upwardly extending arm 8 at the rear of said recess 2. Rotatably mounted in the opening 3 of said plate 1 is the stem of the knob handle 10 and in said arm 8 is rotatably mounted an extension 10 of the outer end of the electrode lead 12 of a mercury switch comprising the horizontal cylindrical envelope 14 of glass, fused quartz or the like which has sealed into one end of the said lead 12 and axially aligned therewith at the other end is the electrode lead 16 to which is mounted said handle 10. Dividing said envelope 14 transversely is the partition 20 of glass, quartz or the like which has an opening 22 which is off the center of said partition 20 and which connects the two chambers into which said partition 20 divides said envelope 1. On the inner ends of said leads 12 and 16 are the annular electrode terminals 24 and 26 and extending through

said opening 22 in a closed position of the 55 switch to connect said electrodes 24 and 26 is the body of mercury 28. Said extension 10 is insulated from said electrode 12 and a flexible connector 30 connects from said electrode 12 to a lead wire 32, the outer end of 60 said connector 30 being mounted to and insulated from said bracket 6. Another flexible lead 34 is connected to said electrode lead 16 and is mounted to but insulated from said bracket 6 at which point it connects to a wire 36.

On said handle 10 on the outside of plate 1 is a stiffly flexible finger 38 which in an open circuit position of the switch springs into the depression 40 in the face of said 70 plate 1 from which it can be moved by rotational pressure on said handle 10. Another depression 42 is provided to receive said finger 38 in a closed position of the switch for holding it closed. The sides of 75 said depressions 40 and 42 which are next each other are in the preferred form slightly sloped or rounded to permit the bringing of said finger 8 by rotational movement to said handle 10 to move the switch from the open to the closed circuit position thereof or vice versa with a movement by the shorter distance between said depressions 40 and 42. The outer sides of said depressions 40 and 42 are made re-entrant in the preferred form 80 to prevent movement of the switch unit to any position other than those in which said finger 38 is in either one of said depressions 40 or 42 or therebetween. Inside said plate 1 is a connector arm 44 carried by said 85 handle 10 and opposite it in said plate 1 is the opening 46 through which from the outside can be viewed characters on said plate 44 for indicating on and off positions of the switch.

In another embodiment of the invention, said conductors 30 and 34 are in the form of spiral springs heavy enough to support the switch 14 and used to aid in the support of or to fully support the switch body and 100 one of said springs can be mounted with the winding in the opposite direction from that of the other to counteract any tendency to a snap movement by said springs. Also, when mounted with the winding in the same 105 direction the springs can be utilized to serve the additional function of imparting movement of the switch in a direction to make

circuit therethrough or in the opposite direction.

While I have shown and described and have pointed out in the annexed claims certain novel features of the invention, it will be understood that various omissions, substitutions and changes in the forms and details of the device illustrated and in its operation may be made by those skilled in the art without departing from the spirit of the invention.

I claim:

1. In combination with a liquid flow switch having a sealed body, axially aligned electrode leads terminating in electrodes in said envelope, and a body of mercury in said envelope for breaking and making the circuit between said electrodes, a wall plate, a bracket extending from said plate, said switch being mounted between said plate and said bracket for rotation about said electrode leads as axes.

2. In combination with a liquid flow switch having a sealed body, axially aligned electrode leads terminating in electrodes in said envelope, and a body of mercury in said envelope for making and breaking the circuit between said electrodes, a wall plate, a bracket extending from said plate, said switch being mounted between said plate and said bracket for rotation about said electrodes, a handle member mounted to one of said electrodes and frictional means for holding said switch in open or closed positions as desired.

3. In combination with a liquid flow switch having a sealed body, axially aligned electrode leads terminating in electrodes in said envelope, and a body of mercury in said envelope for making and breaking the circuit between said electrodes, a wall plate, a bracket extending from said plate, said switch being mounted between said plate and said bracket for rotation about said electrodes, handle means mounted to one of said electrodes at said wall plate, a spring finger carried by said handle and movable thereby over the surface of said plate, said plate having a depression therein into which said finger will move in an open circuit position of the switch and another depression

into which said finger will move in a closed circuit position of said switch.

4. In combination with a liquid flow switch having a sealed body, axially aligned electrode leads terminating in electrodes in said envelope, and a body of mercury in said envelope for making and breaking the circuit between said electrodes, a wall plate, a bracket extending from said plate, said switch being mounted between said plate and said bracket for rotation about said electrodes, handle means mounted to one of said electrodes at said wall plate, a spring finger carried by said handle and movable thereby over the surface of said plate, said plate having a depression therein into which said finger will move in an open circuit position of the switch and another depression into which said finger will move in a closed circuit position of said switch, the sides of said depressions being formed to cause the spring of said finger to permit its movement from either of said depressions to the other.

5. In combination with a liquid flow switch having a sealed body, axially aligned electrode leads terminating in electrodes in said envelope, and a body of mercury in said envelope for making and breaking the circuit between said electrodes, a wall plate, a bracket extending from said plate, said switch being mounted between said plate and said bracket for rotation about said electrodes, handle means mounted to one of said electrodes at said wall plate, a spring finger carried by said handle and movable thereby over the surface of said plate, said plate having a depression therein into which said finger will move in an open circuit position of the switch and another depression into which said finger will move in a closed circuit position of said switch, the sides of said depressions being formed to cause the spring of said finger to permit its movement from either of said depressions to the other and to prevent movement beyond said depressions.

Signed at Hoboken in the county of Hudson and State of New Jersey this 14th day of January, A. D. 1927.

WARREN R. WALKER.
